UNITED STATES PATENT OFFICE.

PEARL N. JONES, OF PITTSBURGH, PENNSYLVANIA, AND JAMES ALBERT EMERY, OF NEW YORK, N. Y.

TIME-POINT-INDICATOR WATCH.

1,412,658.

Specification of Letters Patent. Patented Apr. 11, 1922.

Application filed October 18, 1921. Serial No. 508,561.

To all whom it may concern:

Be it known that we, PEARL N. JONES and JAMES A. EMERY, both citizens of the United States, and residents, respectively, of the city 5 of Pittsburgh, in the county of Allegheny and State of Pennsylvania, and New York, borough of Manhattan, in the county and State of New York, have invented a new and Improved Time-Point-Indicator Watch, of 10 which the following is a full, clear, and exact description.

This invention relates to indicators and has for an object to provide an improved indicator for readily indicating to a motor- 15 man, engineer or other person the time and place of arrival of a car or other conveyance.

Another object of the invention is to provide a time and point indicator for street 20 cars, railways and the like wherein a clock mechanism will indicate not only the time but directly the point at which the car should be at any particular time.

A still further object in view is to provide 25 an arrangement for indicating readily to a motor-man, engineer or other workman, the time and place where he should be during working hours, the structure being such that a set of clock works may be used and fixed 30 permanently in place or an independent watch or other clock mechanism may be used.

In the accompanying drawings—

Figure 1 is a front view of an indicator disclosing one embodiment of the invention. 35

Figure 2 is a sectional view through Figure 1 approximately on line 2—2.

Figure 3 is a rear view of the structure shown in Figure 1.

Figure 4 is a horizontal central sectional 40 view through the structure shown in Figure 3, the watch being omitted.

Figure 5 is a detail fragmentary sectional view through Figure 4 approximately on line 5—5.

45 Figure 6 is a rear view of the dial shown in Figure 1.

Referring to the accompanying drawings by numeral, 1 indicates a body which may be of wood or other desired material, said body 50 being provided with a chamber 2 merging into a notch 3 and having an opening or passageway 12' extending to the opposite side of the body. The body 1 is also provided with an annular offset or recess 4 for receiving a card 5. A suitable number of over-

hanging shoulders 6 and 7 are provided for properly holding the card 5 in the depression 4 without materially covering any part of the card. A clamping screw 8 is provided for firmly clamping the card against the 60 body 1 so as to prevent any accidental rotation. This is necessary in order that the various designations 9 on the card 5 may always remain at the same place and opposite the same numbers on the dial 10 of the watch 65 11. It will be noted that twelve designations or points 9 are provided but a greater or less number may be used without departing from the spirit of the invention.

When the device is used by anyone, as for 70 instance, a motor-man on a street car, a proper indicator will be provided which will not only show the time of day but the points at which the car should be at certain times. In regard to the particular showing of Figure 1, it will be seen that when the minute hand of the watch 11 is pointing at 3 on the watch, it will also point at the designation, 75 45th St. This means that the car should be at 45th St. When the minute hand moves to 80 the designation 4 on the clock it also moves opposite the designation 60th St. By glancing at the device the motor-man may readily see whether or not he is at the place indicated by the minute hand and thereby knows 85 whether or not he is on time.

The reverse side of card 5 is shown in Figure 6 so that when the car reaches the end of its travel the motor-man may remove the card and turn the same over so that the device will properly indicate the location of 90 the car at any time.

In the drawing a watch 11 has been shown but it will be evident that permanent clock mechanism may be provided in body 1 instead of the watch. When the watch is used, a suitable cushion or pad 12 is provided near the opening 12' and the watch is pressed against this cushion by a backing plate 13 provided with suitable cushioning members 95 14. A spring 15 is connected with the backing plate 13 and at 16 with the body 1. A swinging stirrup 17 is provided opposite the connecting member 16 whereby the spring 15 urges the backing plate 13 against the watch 100 and presses the watch tightly against the pad 12 for holding the same firmly in place and against shifting. The notch 3 acts as means for receiving the ring and winding arbor of the watch as shown in Figure 3. 105 110

In the drawing the points or indications 9 have been provided to show a travel of one hour for the car but other rulings could be provided for showing two or more hours 5 without changing the general idea of providing means for indicating the place where the car should be by the way the hands of the time piece point.

What we claim is:—

- 10 A time point indicator comprising a body having an opening in the center thereof and a chamber merging into said opening, an annular cushioning member surrounding said opening, a watch positioned in said chamber 15 and against said annular cushioning mem-

ber, a backing plate for holding said watch in said chamber, an annular cushion member carried by said backing plate positioned to engage said watch, a spring for resiliently holding said backing plate in position, a 20 swinging latch for holding said spring in an operative position and a dial member carried on the face of the body formed with indications thereon designating points along a given route, said designations being arranged 25 so that the hands of the watch must pass them as they rotate.

PEARL N. JONES.
JAMES ALBERT EMERY.
